UNITED STATES PATENT OFFICE

168,148

CULTIVATOR SHOVEL OR SIMILAR ARTICLE

Leroy A. Demorest, Ashley, Ohio

Application July 14, 1951, Serial No. 15,878

Term of patent 14 years

(Cl. D39—1)

To all whom it may concern:

Be it known that I, Leroy A. Demorest, a citizen of the United States, residing at Ashley, in the county of Delaware and State of Ohio, have invented a new, original, and ornamental Design for a Cultivator Shovel or Similar Article, of which the following is a specification, reference being had to the accompanying drawing, forming a part thereof.

Fig. 1 is a perspective view of a cultivator shovel or similar article showing my new design;

Fig. 2 is a side elevational view;

Fig. 3 is a rear end elevational view; and

Fig. 4 is a top plan view.

I claim:

The ornamental design for a cultivator shovel or similar article, substantially as shown.
